UNITED STATES PATENT OFFICE.

JOSEPH DION, OF CHICAGO, ILLINOIS.

DESIGN FOR BROOM-HANDLES.

Specification forming part of Design No. 5,820, dated April 30, 1872.

Specification describing a Design for Broom-Handles, invented by JOSEPH DION, of Chicago, in the county of Cook and State of Illinois.

The nature of my design is fully represented in the accompanying photographic illustration, to which reference is made, and in which—

Figure 1 is a representation of an entire broom. Fig. 2 is an enlarged representation of the ornamented part of the handle.

A represents a broom-handle, to which is attached the broom-brush B. Around the handle, and about the central portion thereof, I

paint the several narrow black bands or rings, *a*, and the wider ones, *b*; between these latter I paint the handle red, as indicated in the illustration by dots, or the clouded part *c*, leaving the balance of the handle of the natural wood color.

What I claim as my invention is—

The design for the ornamentation of a broom-handle, substantially as described.

JOSEPH DION.
